SPINDLE

Ernest D. Meadows, Atlanta, Ga., assignor to
 Meadows Manufacturing Company, Atlanta,
 Ga., a corporation of Georgia

Application May 22, 1950, Serial No. 163,410

1 Claim. (Cl. 308—169)

1

My invention relates to a textile spindle.

It is an object of the invention to provide an improved textile spindle, which will facilitate doffing, and which will minimize vibration of and wear on the bobbins.

It is another object to provide an improved bobbin for use with an improved spindle.

Another object is to improve certain mechanical features of a textile spindle to facilitate and cheapen the manufacture thereof, and, in general, the object is to provide an improved textile spindle and parts thereof.

In my improved spindle, I make the blade very materially shorter than the standard length bobbin, and provide a driving head at the upper end of the spindle, for supporting and driving a standard length bobbin at a point substantially down from the top thereof. A second head is provided on the blade, to fit within the bore of the bobbin at the lower end to guide and steady the bobbin.

In the preferred form, I provide an improved bolster fitting within a bolster case or base, which is itself carried by a rail in the usual fashion. The bolster is preferably made up of separate, readily fabricated pieces subsequently put together so as to provide an improved, yet cheap form of bolster.

In the drawings which show, for illustrative purposes only, preferred forms of the invention—

Fig. 1 is a vertical sectional view through a complete textile spindle and associated bobbin, illustrating features of the invention;

Fig. 2 is an enlarged sectional view of a part of the spindle of Fig. 1;

Fig. 3 is a sectional view, taken substantially in the plane of the line 3—3 of Fig. 1; and

Fig. 4 is a sectional view of the upper part of the spindle of Fig. 1, illustrating a modification.

In the preferred form illustrated, I employ a blade 5, which is supported for rotation in a bolster and bolster case. The blade 5 above the whorl is relatively short and stubby and has a head 6 at the upper end, which head is preferably of steel or the like, and may be secured to the blade as by means of a press fit, as will be clear from the drawings. The effective length of the blade is much less than the length of a standard bobbin and is preferably of such length as to engage a standard length bobbin about one-third or one-quarter the way down from the top. The blade has a second head 7 down from the upper end, which head 7 may correspond to the usual acorn, and may be a part of the usual whorl 8, as will be understood. The head 6 is arranged for driving and supporting a bobbin 9, and in the form shown, the upper head 6 has a tapered outer surface 10, which is adapted to interfit with the

2

surface 11 in the bore of the bobbin 9, which surface 11 may be correspondingly tapered so as to provide a good drive fit between the spindle blade and the bobbin and so as to adequately support the bobbin 9. At the lower end, the bore of the bobbin is preferably truly cylindrical, and the head 7 is likewise preferably truly cylindrical so as to provide a floating fit, as indicated at 12, between the lower end of the bobbin and the head 7. The fit 12 is sufficiently close as to prevent any substantial vibration of the bobbin, and yet is sufficiently loose so that only the joint at 10—11 need be broken in doffing. Between the heads 6 and 7, the blade 5 is preferably encased in an adapter 13, preferably of plastic or the like, so as to make the blade of substantially uniform diameter from the top down to the whorl.

In the form shown in Fig. 1, the bobbin 9 is truly cylindrical on the outside, while in Fig. 4, the bobbin 9' is tapering on the outside, being larger at the bottom than it is at the top. Thus, by making the bobbins with the proper bore and configuration, straight cylindrical bobbins or tapered bobbins may be used interchangeably on the same spindle. The bobbins are preferably formed of plastic, which may be Bakelite or similar material, and which will maintain the bearing surfaces without undue wear. If desired, the bottom of the bore of the bobbin may be vertically ribbed or fluted so as to permit passage of yarn and thus prevent cutting at doffing time.

The blade 5 is preferably supported in a bolster 14, which is itself supported in a bolster base or case 15. The bolster may be formed of a metal tube 16, having a step-bearing block 17, with a sleeve or skirt press-fitted or otherwise telescopically fitted and secured to the bottom of the tube, in the present showing the tube being on the outside rather than inside the bearing block skirt. This step-bearing block has a step-bearing for the bottom end of the blade, and may have lubricant passages 18 for conducting lubricant to the step-bearing. The bearing block 17 may rest upon a bottom plug 19, press-fitted or otherwise secured to the bottom of the base 15. Keying means, such as the pin 20, may be employed for preventing the bearing block 17, and in fact the entire bolster, from rotating in the case. The bolster tube 16 at the upper end is provided with a bearing adapter 21, which preferably has a downwardly extending sleeve or skirt 22, preferably press-fitted and telescopically secured to the upper end of the bolster tube 16; in the present instance the adapter skirt is fitted inside of the tube rather than outside thereof. If desired, the tube may be crimped, as indicated at 23, for holding the adapter 21 in the upper end of the tube. The adapter has a bore 24 for

the passage of the blade 5, and the adapter is provided with a counterbore 25 for the reception of an antifriction bearing, which in the present instance includes a bearing sleeve 26 and cylindrical bearing rollers 27, held in a suitable cage 28. The bearing sleeve 26 and rollers are held in place as by means of annular abutment rings 29-29 at the top and bottom. A washer 30 at the top serves to hold the entire bearing assembly in the counterbore, and the upper edge of the sleeve defining the counterbore may be beaded over, as indicated at 31, so as to engage the washer and permanently secure the bearing in the bearing adapter. The bearing adapter has a sliding fit within the upper tubular end 32 of the base or case 15, so that the bolster is centered within the case at the top. The step-bearing block 17 at the bottom of the bolster tube has a clearance of about 0.015" in the bolster case so that the blade may seek its own center of rotation. Slight movement of the bolster in the case is permitted by the clearance between the adapter 21 and the case. Oil in the case acts as a damper to damp the movement of the bolster in the case. At a point above the antifriction bearing, and below the top 32 of the case 15, the blade 5 is provided with an oil slinger 33, which is preferably located within the skirt of the whorl, which skirt, as usual, extends down over the top of the case, and the center of the belt-receiving portion of the whorl is preferably just about in line with the antifriction bearing.

The case 15 may consist of a tube threaded intermediate the ends at 34, for the reception of a nut (not shown) for securing the case to the usual rail (not shown). The tube or case 15, as stated, may be closed at the bottom as by means of the plug 19, and at a point above the threads 34 the case preferably has a radial flange 35, which may fit into a counterbore 36, formed in a lubricator ring 37, which has a bore to tightly fit the outside diameter of the tube 15. The lubricator ring has a passage 38 communicating with a passage in the case 15, so that oil introduced into the lubricator will reach the oil reservoir formed by the case at the outside of the bolster tube. It will be understood that the lubricator ring 37 in the form shown is adapted to support the case 15 and to rest on the top of the rail and be held in place by the usual nut (not shown) screwed onto the case 15.

The oil from the reservoir formed in the case at the outside of the bolster tube 16 is adapted to reach the step-bearing through the passages 18 and to reach the inside of the bolster case around the lower part of the spindle through one or more holes 38' in the tube 15. These holes are preferably inclined, and may be formed by grinding or otherwise so that at the inside there is a very sharp edge defining the hole or holes in the tube, as will be clear particularly from Fig. 3. At a point toward the top of the tube 15, and beneath the bearing, the bolster tube 15 preferably has one or more holes 39, similar to the holes 38 heretofore described. Thus, when the spindle blade rotates, oil within the bolster tube will be fed upwardly and will be given somewhat of a spiral motion so that when it reaches the upper hole or holes 39, the oil will be forced out past the sharp knife edge of the hole and will again drop down on the outside of the tube 15 into the reservoir. Thus, oil will enter the bolster tube at the bottom, will be fed up by the rotation of the blade, and will pass out of the

tube before it reaches the top of the bolster tube, thus providing for proper circulation and cooling, and yet without undue agitation or churning of the oil. Enough oil will be carried up on the blade 5 to adequately lubricate the antifriction bearing at the top by direct conduction on the blade. Any surplus oil, as indicated above, will be trapped by the oil slinger 33, and will descend through the bearing and down the inside of the adapter and bolster tube.

It will be seen that all of the parts of my improved spindle are exceedingly simple in construction and may be readily manufactured. The assembly of the various parts is quite simple, and the completed spindle is cheap to manufacture, very sturdy in construction, and will give excellent service throughout a long life.

The improved short spindle blade with the driving head at the top to support and drive a bobbin from a point well down from the top thereof is much superior to the prior art spindles which drive and support the bobbin from the bottom and merely guide the bobbin on the upper end of the blade substantially down from the top of the bobbin. The prior art spindles referred to soon wear the inner guide surface of the bobbin to such an extent that vibration becomes excessive and the bobbin must be replaced. My improved blade and bobbin fit tightly at the top of the blade so the bobbin is supported and driven from that point. The tight driving fit prevents substantially all wear, and vibration of the bobbin is reduced to a minimum; thus, bobbin life is prolonged, and accuracy and stability maintained. The short blade with the driving head at the top makes for ease in doffing in that the bobbin need be raised only the length of the short blade.

While the invention has been described in considerable detail, and preferred forms illustrated, it is to be understood that various changes may be made within the scope of the invention as defined in the appended claim.

I claim:

In a textile spindle, a bolster including a tube having a step bearing at the bottom and an antifriction bearing at the top, said tube having an opening toward the top thereof, which opening has a sharp edge at the inside of said tube, whereby oil flowing up and whirling in said tube due to blade rotation will flow out of said hole, and a base for receiving said bolster and holding an oil supply at the outer side of said tube.
